UNITED STATES PATENT OFFICE.

JOHN EARL JACKSON, OF DETROIT, MICHIGAN.

MOTOR ATTACHMENT FOR PLAYER PIANOS.

Application filed October 13, 1923. Serial No. 668,330.

To all whom it may concern:

Be it known that I, JOHN E. JACKSON, a citizen of the United States, residing at Detroit, in the county of Wayne and State 5 of Michigan, have invented certain new and useful Improvements in Motor Attachments for Player Pianos, of which the following is a specification.

This invention relates to player pianos 10 and has particular reference to a motor attachment therefor by means of which the instrument may be played automatically in lieu of the use of the usual foot operated mechanism or pedals.

15 The primary object of the invention is to provide a device of the above kind which embraces the desired qualities of simplicity and durability of construction as well as efficiency in operation.

20 Other objects will appear as the nature of the invention is better understood and the same consists in the novel form, combination and arrangement of parts hereinafter more fully described, shown in the accompanying drawings, and claimed.

In the drawings, wherein like reference characters indicate corresponding parts throughout the several views—

25 Figure 1 is a front elevational view, partly broken away of a player piano provided with a motor attachment in accordance with the present invention.

Figure 2 is an enlarged fragmentary vertical sectional view of the device shown in 30 Figure 1, taken through the casing of the motor, and

35 Figure 3 is a fragmentary elevational view partly broken away of the motor.

Referring more in detail to the drawings, 40 5 indicates the case of an ordinary player piano within which is arranged a longitudinal crank shaft 6 having the crank 7 thereof operatively connected by means of links 8 with the usual pedals 9 by means of 45 which the pump or bellows of the piano are usually operated. The shaft 6 may be suitably journalled in the lower ends of depending bearing arms 10 that are attached at their outer ends to the top of the case 5 as 50 clearly shown in Figure 1, and this shaft 6 is operatively connected with the power shaft 11 of a spring motor 12 by means of a sprocket gearing indicated generally at 13. The sprocket gearing consists of an endless 55 chain passing around aligned sprocket wheels upon the motor shaft 11 and the ad-

jacent end of the shaft 6, the motor 12 being rigidly mounted within the case 5 at one end of the latter.

The motor 12 is of the spring driven type 60 comprising a spring 14 which operates a driving gear 15 which meshes with a spur pinion 16 fixed upon the shaft 11, and the driving gear 15 is mounted upon a winding shaft 17 that projects outwardly through the 65 adjacent end of the case 5 and is provided with a crank 18 by means of which the spring 14 may be rewound as is well known and usual in spring motor constructions.

In order to provide a simple and desirable form of stop for the motor 12, so 70 that the player piano may be rendered operative or inoperative at will, I provide a cam break shoe 19 upon a cam lever 20 that is journalled upon the pin 21 within 75 the casing of the motor 12, the cam shoe 19 being disposed to move into and out of engagement with the adjacent side of the driving gear 15 of the motor. The upper end of the lever 20 extends horizontally and outwardly through an arcuate slot 22 provided in the front of the case 5 as shown in Figure 1, said upper end thus forming a finger piece 23 by means of which the cam 19 may be actuated for starting 80 and stopping the motor and consequently 85 controlling the operation of the pedals 9 which operate the bellows or pumps of the piano.

It is believed that the construction and 90 operation, as well as the advantages of the invention will be readily understood and appreciated by those skilled in the art from the foregoing description and it is noted that minor changes may be made without departing from the spirit and scope of the invention as claimed.

What I claim as new is:

1. In combination with a player piano embodying a case and operating pedals, a 100 longitudinal crank shaft journalled within the case of the piano and having cranks, links operatively connecting the cranks of said shaft with said pedals, a spring motor within the case adjacent one end of 105 the latter and operatively connected to said crank shaft, externally disposed means for rewinding said spring motor from a point at one end of the piano case, and means adjacent said rewinding means for rendering the motor operative or inoperative 110 at will.

2. In combination with a player piano embodying a case and operating pedals, a longitudinal crank shaft journalled within the case of the piano and having cranks, 5 links operatively connecting the cranks of said shaft with said pedals, a spring motor within the case adjacent one end of the latter and operatively connected to said crank shaft, externally disposed means 10 for rewinding said spring motor from a point at one end of the piano case, and means adjacent said rewinding means for rendering the motor operative or inoperative at will, said last named means comprising a cam shoe carrying lever having its upper end extending horizontally through the case, and said spring motor comprising a driving gear with one side 15 of which said cam shoe is adapted to be engaged for stopping the motor.
3. In combination with a player piano having a case and operating pedals, of a motor arranged within the case and operatively connected to said pedals, means for 20 rendering said motor operative or inoperative at will, said motor being of the spring driven type, and a winding shaft for the motor projecting through an opening in one end of the case.
4. In combination with a player piano 25 having a case and operating pedals, of a motor arranged within the case and operatively connected to said pedals, and means for rendering said motor operative or inoperative at will, said motor being of the 30 spring driven type, and a winding shaft projecting through an opening in one end of the case, the operative connection between the pedals and the motor comprising a crank shaft within the case having 35 cranks, links connecting the cranks to the pedals, gearing between one end of said crank shaft and the shaft of the motor, and means to operate said winding shaft.

40 In testimony whereof I affix my signature.

45 JOHN EARL JACKSON.
